UNITED STATES PATENT OFFICE

GEORG WEYLAND, OF FRANKENTHAL, GERMANY

MULTISTAGE HOT-WATER CENTRIFUGAL PUMP

Application filed September 7, 1929, Serial No. 391,011, and in Germany September 15, 1928.

This invention relates to a multi-stage hot-water centrifugal pump, and the primary object thereof is to eliminate the difficulties which arise in connection with the packing of the stuffing box on the high pressure side due to the fact that the stuffing box cannot be maintained as a tight joint at the high pressures and temperatures occurring.

On the other hand the stuffing box packing on the high pressure side is capable of fulfilling its object if hot water is prevented from reaching the stuffing box.

This in the case of the invention may be most readily accomplished by taking as a basis a multistage hot-water centrifugal pump, which pre-heats the liquid between two pressure stages, and in which a sealing liquid chamber is provided between the stuffing box and the so-called leakage water chamber. The passage of the hot water to the stuffing box may then be prevented by the fact that in the said sealing liquid chamber a higher pressure and lower temperature is maintained than prevails in the leakage water chamber. In this manner the stuffing box is insulated against passage of the water by relief of the pressure.

According to one form of embodiment of the invention the sealing liquid chamber and the leakage water chamber are connected to the same pressure stage, viz., the sealing liquid chamber at the outlet socket for the liquid which is not pre-heated, and the leakage water chamber on the other hand at the inlet socket for the pre-heated liquid. In this manner it is accomplished that the drop in pressure in the inlet socket, created by the resistance of the delivery liquid in the pre-heater, may be utilized for producing the difference in pressure and temperature in the sealing liquid chamber and the leakage water chamber.

The invention will now be described more fully with reference to the accompanying drawing, which illustrates a possible form of embodiment of the invention by way of example.

Fig. 1 is a part longitudinal section through the high pressure side of the pump. Fig. 2 being a diagrammatical represen-

tation of the pump with the pre-heater.

In the example according to the drawing the pump is assumed to be one having eight pressure stages, and wherein the second stage is in connection with the pre-heater, so that the pre-heated water is introduced in the third stage and the further stages raise the pre-heated water to boiler pressure.

The cold water enters through the inlet socket A in the first stage (Fig. 2), and passes through the outlet socket B of the second stage into the pre-heater V, from which the pre-heated water is conducted into the inlet socket C of the third stage. From the outlet socket D of the eighth stage the hot water is conducted under high pressure to the boiler.

E is the stuffing box, which is to be protected against the entry of hot water from the so-called leakage water chamber F. Between the two parts E and F is situated the sealing liquid chamber G. According to the invention the stuffing box E is protected against the passage of hot water by the fact that in the sealing liquid chamber G a higher pressure and a lower temperature are maintained than in the leakage water chamber F. The higher pressure prevailing in the sealing liquid chamber G and also the lower temperature then protect the stuffing box E against the entry of hot water from the leakage water chamber F. For this purpose the sealing liquid chamber G and the leakage water chamber F are connected to the same pressure stage.

Practically the same pressure prevails in the socket B, which conducts the cold feed water to the pre-heater V, and the socket C, which passes the pre-heated feed water to the third pressure stage. Accordingly, the most simple construction consists in connecting the sealing liquid chamber G to the socket B by means of a pipe H, and the leakage water chamber F to the socket C by means of a pipe I.

It will be understood that no restriction is made to the particular form of embodiment illustrated in the drawing, and that various modifications may be made within the meaning of the above description and the ap-

pended claims without departing from the spirit of the invention.

What I claim as new and desire to secure by Letters Patent is:

- 5 1. In a multi-stage hot-water centrifugal pump, a pre-heater for pre-heating the delivery liquid between two of the pressure stages of the pump, a leakage water chamber, a stuffing box, and means for preventing access of hot water to the said stuffing box by maintaining at a point between the said stuffing box and the said leakage water chamber a higher pressure and a lower temperature than prevails in the said leakage water chamber.
- 10 2. In a multi-stage hot-water centrifugal pump, a pre-heater for pre-heating the delivery liquid between two of the pressure stages of the pump, a leakage water chamber, a stuffing box, and a sealing liquid chamber between the said stuffing box and the said leakage water chamber for preventing access of hot water to the said stuffing box by maintaining in the said sealing liquid chamber a higher pressure and a lower temperature than prevails in the said leakage water chamber.
- 15 3. In a multi-stage hot-water centrifugal pump, a pre-heater for pre-heating the delivery liquid between two of the pressure stages of the pump, a leakage water chamber, a stuffing box, and a sealing liquid chamber between the said stuffing box and the said leakage water chamber, and means for establishing connections between the said leakage water chamber and the said sealing liquid chamber, respectively, and the same pressure stage of the pump, viz., the sealing liquid chamber to the outlet socket for the delivery liquid which is not pre-heated and the leakage water chamber to the inlet socket for the pre-heated delivery liquid, whereby the drop in pressure resulting by the resistance of the delivery liquid in the said pre-heater is utilized for producing differences in pressure and temperature in the said sealing liquid and leakage water containers.

In testimony whereof, I affix my signature.
GEORG WEYLAND.
